UNITED STATES PATENT OFFICE.

WILLIAM H. BELL, OF THE UNITED STATES ARMY.

INTRENCHING-TOOL.

SPECIFICATION forming part of Letters Patent No. 506,091, dated October 3, 1893.

Application filed March 27, 1893. Serial No. 467,849. (No model.)

To all whom it may concern:

Be it known that I, WILLIAM H. BELL, a lieutenant colonel in the United States Army, and a citizen of the United States, residing at 5 Denver, in the county of Arapahoe and State of Colorado, have invented certain new and useful Improvements in a Combination Canteen and Intrenching-Tool; and I do hereby declare the following to be a full, clear, and exact description of the invention, such as will enable others skilled in the art to which it appertains to make and use the same.

My invention relates to improvements in intrenching tools, adapted to be carried on canteens, and it consists in certain novel features hereinafter described and claimed.

Reference is had to the accompanying drawings, in which the same parts are indicated by the same letters throughout the several 20 views.

Figure 1 represents a side elevation of the improved combination canteen and intrenching tool. Fig. 2 represents an end view of the same. Fig. 3 represents a perspective 25 view of the intrenching tool detached.

A represents the canteen which is constructed in the usual way, and is provided with a stopper A' connected to the canteen by the chain a' attached near the base of the 30 neck of the canteen a, as shown in Fig. 2. Eyes a² are provided in the sides of the canteen for the purpose of attaching the lanyard a³ which steadies the intrenching tool. The canteen is suspended by means of strap C in 35 the usual way.

B represents the intrenching tool or shovel, which is provided with two handles B' one on either side of the aperture B⁰ or loop which is adapted to allow the neck of the canteen 40 to enter freely. The intrenching tool is made of such a form as to fit the contour of the canteen more or less accurately, and is stiffened by ribs b and b', which preferably run down to a tip b², which serves as the point of the 45 shovel or trowel-like intrenching tool. These ribs may be made either integral with the intrenching tool, or may be riveted or otherwise attached thereto, and the shape of these 50 ornaments the ribs may be curved up

ward as shown at b', or may be arranged in any desired manner.

The canteen and intrenching tool are ordinarily carried as shown in Figs. 1 and 2, but when it is desired to use the intrenching tool, 55 the stopper A' of the canteen is temporarily removed from the nozzle, or neck thereof, the intrenching tool is slipped over the neck, the stopper is replaced and the tool is ready for use. 60

To use the intrenching tool it is grasped by both the handles B', and is used first with the concave side next the person and tool nearly perpendicular to break up the earth; and when sufficient earth is broken the tool is 65 turned over and used as a shovel to throw out the broken earth. In sand or loose earth the latter method is used entirely.

By having the intrenching tool provided with two handles, the weight of the whole 70 body may be better applied in digging with the tool, and there is a less tendency of the tool to upset than is the case with a shovel or trowel of the ordinary construction.

It will be seen that the tool occupies very 75 little room, and is not likely to swing about on the canteen or interfere with the movements of the person carrying the same; also that the canteen can be used for drinking without removing the intrenching tool, the 80 distance between the handles B' being sufficient for the admission of the parts of the face contiguous to the mouth.

The tool may be made of steel, aluminum bronze, or any other metal suitable for the 85 purpose.

Having thus described my invention, what I claim, and desire to secure by Letters Patent of the United States, is—

1. An intrenching tool adapted to be attached to a canteen, provided with an aperture or loop adapted to slip over the neck of the canteen, and a body fitting snugly over the side of the canteen, substantially as and for the purposes described. 90

2. An intrenching tool adapted to be attached to a canteen, provided with a loop adapted to slip over the neck of the canteen and a body fitting snugly over the side of the canteen, and two handles placed one at either 95 100

side of said loop, substantially as and for the purposes described.

3. An intrenching tool adapted to be attached to a canteen, provided with an aperture or loop B° adapted to slip over the neck of the canteen, handles B' on either side of said aperture, and strengthening ribs on the back of said tool, terminating in a point b°, and connected to said handles, the said tool

fitting snugly over the side of the canteen, substantially as and for the purposes described.

In testimony whereof I affix my signature in presence of two witnesses.

WILLIAM H. BELL.
